Inventor:

UNITED STATES PATENT OFFICE.

ALEXANDER J. ROUX, OF NEW YORK, N. Y.

DESIGN FOR A DRAWER-HANDLE.

SPECIFICATION forming part of Design No. 16,587, dated March 23, 1886.

Application filed July 9, 1885. Serial No. 171,121. Term of patent 7 years.

To all whom it may concern:

Be it known that I, ALEXANDER J. ROUX, a citizen of the United States, residing in the city, county, and State of New York, have invented and produced a new and original Design 5 for a Drawer-Handle, of which the following is a full, clear, and exact description, reference being had to the accompanying drawings, in which—

10 Figure 1 shows a front view, and Fig. 2 an edge view of the same.

The leading features of my design consist in open-work plates and open-work semi-elliptical band connecting these plates, the whole 15 forming one piece of casting. In front view the plates at the ends are segmental in shape, and consist in radial lines with intermediate open-work and circumscribing fillet or band.

At the upper and lower extremities are the holes for screws. The semi-elliptical band 20 has its upper and lower edges beaded and molded, and its central part composed of cross-bands ornamented with raised borders and so spaced as to leave a number of large openings. This central part of the band is convex in section. 25

I claim—

The design for a drawer-handle herein shown and described, the same consisting of segmental plates with ornamentation in radial lines and 30 semi-elliptical band with open-work ornamentation connecting said plates. 30

ALEXANDER J. ROUX.
